Harden F. Taylor INVENTOR
W. V. Pitchard BY ATTORNEY

UNITED STATES PATENT OFFICE.

HARDEN F. TAYLOR, OF BRONX, NEW YORK, ASSIGNOR TO THE ATLANTIC COAST FISHERIES COMPANY, OF NEW YORK, N. Y., A CORPORATION OF MAINE.

PACKAGING.

Application filed April 9, 1928. Serial No. 268,394.

This invention relates to wrapping of comestibles, such as fillets of fish, cuts of meat, dressed fish and the like, in either their fresh or frozen state, and more particularly to the 5 wrapping of frozen fillets of fish.

Comestibles of the type above-mentioned are characteristic and peculiar in that they do not have any definite or uniform shape or size. The irregular dimensions of these products render it difficult to wrap them neatly and form a shapely package. Furthermore, these peculiar characteristics render it difficult to pack these products in bulk in an orderly and uniform way. The ordinary and 10 usual methods of wrapping these products consist in manually wrapping the products in paper or in placing the goods in boxes or cartons. These methods of wrapping have many disadvantages. In the case of wrapping in 15 paper, unshapely, irregular and nonuniform packages are obtained. If the products are fresh or defrosted from the frozen condition, they may be damp or wet, and various means and precautions must be taken to prevent soiling of one's clothes or contamination of foodstuffs. In cases where a box or carton is employed to wrap the product, a shapely package 20 is obtained, but various means to prevent soiling of clothes and contamination of foodstuffs 25 must be provided. Still, further, when a box or carton is used, there is usually an excess of space. This is very objectionable, especially when it is desired to place the package in cold storage to keep the product in the frozen 30 state, in that it takes up more storage space than necessary, and cold storage space is expensive.

I have found that I can overcome the above-mentioned disadvantages by disposing the 40 product to be wrapped on a support and then wrapping the two together in a waterproof material, whereby a uniform, shapely and ornamental package is obtained.

It is, therefore, an object of this invention 45 to wrap comestibles, such as fillets of fish, cuts of meat, dressed fish and the like, in their fresh or frozen state and to form packages which are uniform, shapely, ornamental and do not have a large excess of vacant spaces.

50 It is a further object of this invention to wrap comestibles of the type mentioned by placing the comestibles on a support and then to form a package by wrapping the support and fish in some waterproof material.

Another object of this invention is to produce substantially uniform and shapely packages of frozen fillets of fish which may be easily and conveniently handled, packed in bulk in an orderly and uniform manner, or kept in cold storage until they are ready for 55 distribution or use.

A specific object of this invention is to produce a package containing a waxed cardboard support on which is disposed a fillet and a waxed paper wrapper enveloping said support and fillet.

Further objects will appear from the following description, appended claims and the accompanying drawings which form a part 60 of this specification and in which:

70 Figure 1 is a perspective view of a package of a fillet of fish wrapped according to my invention; and

Figure 2 is a vertical section through a large carton or container in which the packages are packed in bulk for shipment or otherwise.

According to my invention, I place the comestible on a support and then wrap the two together in a wrapper, preferably of a waterproof material.

80 In the drawings in which I have represented one modification of my invention, the reference numeral 1 designates a frozen fillet of fish. The fillet 1 is placed on a support 2 with its flat surface in contact therewith and its rounded or curved portion uppermost. Various materials may be used for the support. I have found that a strip of cardboard 85 functions satisfactorily.

90 In order to enhance the appearance of the package, I may make the support in various shapes and forms and especially in shape of various kinds of fish. When a transparent wrapper is used, the appearance of the package may still further be enhanced by decorating or ornamenting the support. I have ornamented the support by providing it with various colored pictures and/or printed matter

such as recipes. To prevent any deleterious 95 effect to the support that may be occasioned by the moisture or dampness present in fresh or defrosted comestibles of the above-mentioned type, I may waterproof or otherwise treat the support. Various waterproofing 100 compositions and substances may be used. I have in practice found that paraffin wax effects the desired functions and gives satisfac-

tory results. To make the package uniform and of the same size, I use a uniformly sized support.

After the fillet has been placed upon the cardboard or other support, as above described, both the support and the comestible are wrapped together in some wrapping material 3. Due to the support and the disposition of the fillet thereon, the wrapping may be done either manually or by machine. Preferably, I perform the wrapping operation by machine. By so doing the sanitary conditions are better and I obtain more uniformly wrapped packages.

15 The wrapper may encompass or envelope the support and fillet in any manner whatsoever. I have shown it as having its longitudinal edges 4 overlapping and the ends 5 flapped over. It is, of course, apparent that 20 the wrapping may be made so as to be of any other shape. If desired, the wrapper may be sealed at its overlapping edges 4 and flaps 5, thus providing a substantially sealed waterproof package. By this means, if the fillet 25 should become defrosted it would not soil one's clothing or contaminate comestibles with which it may come in contact.

The wrapper 3 may be any well-known waterproof material such as waterproof paper, waterproof parchment paper, sheets of regenerated cellulose or metallic foils. Preferably, I use wax paper. If desired, the wrapper may also be ornamented in any manner whatsoever.

35 The individual package lends itself to be uniformly packed in bulk in cartons, boxes or other containers as clearly illustrated in Figure 2. In packing, the individual packages 6 are arranged in staggered relation in 40 rows or layers in the container 7. In the first or bottom layer 8, the individual packages are arranged end to end and/or side by side with their flat surfaces in contact with the bottom of the container and their curved surfaces uppermost. In other words, the packages in the first layer are placed with the fillet surfaces 45 upward. The second layer 9 is formed by placing the individual packages with their rounded or fillet surfaces downward and bridging the spaces 10 formed by two adjacent packages in the bottom layer. In other words, the packages of the second row or 50 layer 9 are arranged in staggered relation to the packages in the layer 8 with their rounded surfaces contacting. The third layer 11 is 55 similar in arrangement to layer 8 and layer 12 corresponds to layer 9. These layers are repeated until the container is full. In this way I can pack in bulk the individual packages 60 of fish in a uniform and orderly manner.

Packages of fish, prepared as above-described, are of regular contour or shape and have definite and uniform dimensions. Due to the ornamentation and shape of the support 65 and/or the wrapper, the package has an orna-

mental appearance. Since the support has been waterproofed and the wrapping paper is of a waterproof material, defrosting of the frozen comestible will in no way affect the package. The water, moisture or dampness 70 will be retained within the package, and thus it will be unable to effect any injurious results. The package is also capable of being very easily handled and uniformly packed in bulk, as above described. It has very little excess 75 space and, therefore, when placed in cold storage it will occupy a minimum amount of space.

I do not intend to limit myself to the exact details above-described, since it is obvious 80 that various modifications and changes can be made without departing from the nature of the invention.

I claim:

1. In a package for a comestible, means to 85 substantially prevent escape of any liquids present or formed therein, comprising a support of waterproof material of substantial rigidity on which said comestible is disposed and a waterproof wrapper enveloping said 90 comestible and support.

2. In a package for a comestible, means to substantially prevent escape of any liquids present or formed therein, comprising a support of waterproof cardboard of substantial 95 rigidity on which said comestible is disposed and a waterproof wrapper enveloping said comestible and support.

3. In a package for a frozen comestible, means to substantially prevent escape of any 100 liquids present or formed therein, comprising a support of waterproof material of substantial rigidity on which said comestible is disposed and a waterproof wrapper enveloping said 105 comestible and support.

4. In a package for a frozen comestible, means to substantially prevent escape of any liquids present or formed therein, comprising a support of waterproof cardboard of substantial 110 rigidity on which said comestible is disposed and a waterproof wrapper enveloping said comestible and support.

5. In a package for frozen fish, means to substantially prevent escape of any liquids present or formed therein, comprising a support of waterproof material of substantial 115 rigidity on which said fish is disposed and a waterproof wrapper enveloping said fish and support.

6. In a package for frozen fish, means to 120 substantially prevent escape of any liquids present or formed therein, comprising a support of waterproof cardboard of substantial rigidity on which said fish is disposed and a waterproof wrapper enveloping said fish 125 and support.

7. In a package for a frozen fillet of fish, means to substantially prevent escape of any liquids present or formed therein, comprising a support of waterproof material of substan- 130

tial rigidity, said fillet being disposed with its flat surface in contact with said support and a waterproof wrapper enveloping said fillet and support.

5 8. In a package for a frozen fillet of fish, means to substantially prevent escape of any liquids present or formed therein, comprising a support of waterproof cardboard of sub-

stantial rigidity, said fillet being disposed with its flat surface in contact with said support and a waterproof wrapper enveloping said fillet and support. ¹⁰

In testimony whereof, I have affixed my signature to this specification.

HARDEN F. TAYLOR.
